UNITED STATES PATENT OFFICE.

JOHN J. VOORHEES, OF JERSEY CITY, NEW JERSEY, ASSIGNOR TO THE NEW JERSEY CAR SPRING AND RUBBER COMPANY, OF NEW JERSEY.

DESIGN FOR A RUBBER MAT.

SPECIFICATION forming part of Design No. 21,707, dated July 12, 1892.

Application filed April 15, 1892. Serial No. 429,363. Term of patent 14 years.

To all whom it may concern.

Be it known that I, JOHN J. VOORHEES, a citizen of the United States, residing at Jersey City, in the county of Hudson and State 5 of New Jersey, have invented and produced a new and original Design for a Rubber Mat, of which the following is a specification.

This invention relates to a new design for rubber mats; and it consists in a mat having 10 a series of corrugated trapezoidal or lozenge shaped sections arranged to form a substantially star-shaped figure, the corrugations of the adjoining sections being placed in varying directions, and the whole set within a 15 border formed of corrugated and plain bands, as shown.

The figure illustrated in the drawing is a top view of the design as adapted to a mat of substantially square form.

20 The central figure of the mat is composed of sections *a b a' b'*, of substantially trapezoidal or lozenge shape, grouped together so

that the lower angles of the sections meet in a point and the upper angles form the points of a substantially star-shaped figure. These 25 sections *a b a' b'* are corrugated in varying directions. Thus the sections *a* and *a'* in the drawing are represented as corrugated in a direction parallel to the longer axis of said sections, while *b* and *b'* are corrugated in a 30 direction parallel to the shorter axis of the sections. This central star-shaped figure is surrounded by the inner border *c* and outer border *d*, which borders are also corrugated. The corrugated borders *c* and *d* of the mat 35 are separated by a band *e* of uncorrugated rubber.

What I claim is—

A design for a rubber mat, substantially as shown and described.

JNO. J. VOORHEES.
